ADJUSTABLE CHOKE FOR OIL WELLS

Walter Eugene Hammock, Garland, Tex.

Application April 21, 1947, Serial No. 742,935

3 Claims. (Cl. 277—57)

1

This invention relates to flow regulating devices for oil wells, and the like, and it has particular reference to apparatus for arrangement in a flow line to control the flow of well fluid to storage, and its principal object resides in the provision of a compact and economical structure embodying features of design effectively adapting the same to the accurate control of oil flowing through the tubing to storage, and relates to the improvements in flow regulating means covered by Letters Patent issued to Jesse L. Oehler, Number 2,150,077 and dated March 7, 1939.

Another object of the invention is that of providing a flow control device in which is arranged a plurality of flow ports having renewable seats of abrasive and corrosion resistant materials, such as carbide, or other suitable substance.

Broadly, the invention embraces the provision of a self contained valve structure, completely sealed and capable of ready adjustment with a minimum of effort.

While the foregoing objects are paramount, other and lesser objects will become manifest as the description proceeds, taken in connection with the appended drawings wherein:

Figure 1 is a vertical sectional illustration of the invention, taken on lines 1—1 of Figure 2, showing the arrangement of adjustable valve stems, seats and closures.

Figure 2 is a plan view of the invention.

Figure 3 is a perspective illustration of one of the adjustable stems and its self-adjusting seat engaging element.

Figure 4 is a lateral cross-sectional view of the invention, taken on lines 4—4 of Figure 1, showing the top of the ported disk member.

Figure 5 is a lateral cross-sectional view, taken on lines 5—5 of Figure 1, showing an inverted plan view of the disk member, and

Figure 6 illustrates, in perspective, the head member and connected disk member, and showing the adjustable stems and one of the ports.

The invention accordingly comprises a hollow body member 10, preferably cylindrical in form, having a conical or reduced portion 11 at its lower end terminating in a nipple 12 threaded to afford a coupling means by which the device can be connected into a flow line. Interiorly of the body 10, and spaced above the shoulder α defined by the tapered portion 11, is formed an annular shoulder 13 providing a seat for a disk 14 arranged in the manner shown in Figure 1.

The upper end of the body member 10 is 55 The disk 14 is rigidly connected to the head

2

open and is exteriorly threaded. A head member 15 is provided to be conformably seated in the body member 10 to close the upper end and is formed with an annular circumferential flange 16 intermediate its top and bottom which rests upon the upper rim 17 of the body member 10 while the annular skirt 18 of the head member 15 extends downwardly into the body 10 in a relatively close association therewith. The upper portion 19 of the head member 15 extends above the body 10, as illustrated in Figure 1.

The head member 15 is secured to the body member 10 by a flanged ring 20 which is interiorly threaded to engage the threads on the exterior upper portion of the body 10, the flange 21 of the ring 20 bearing upon the annular flange 16 when the ring 20 is threaded thereagainst. Dowel pins 22 are secured in the flange 16 and spaced around the same, as illustrated in Figures 1 and 6, engageable with corresponding bores 23 in the upper rim 17 of the body 10 and by which the head member 15 can be axially adjusted with respect to the body 10.

The body member 10 has a central interiorly threaded bore 24 providing for the connection of the assembly into a flow line. Arranged about or on each side of the threaded bore 24 are a plurality of bores 25, each formed with annular offsets 26 in their lower ends, bushings 27 are fitted therein, their flanged lower ends 28 engaging the annular offsets 26, as in Figure 1.

The bushings 27 have internal threaded portions 29 in their lower ends whose diameters are slightly greater than the remaining portion 30 of the bore above the threads. A valve stem 31, illustrated in detail in Figure 3, is adapted to be threadedly adjustable in each of the bushings 27 and has an enlarged threaded section 32 engageable with the threads 29 by which these members can be adjusted vertically in the head member 15. A plurality of grooves 33 are formed internally of the bushings 27 above the threaded sections 32 in which packing rings 34 of rubber, neoprene, or the like, are arranged to provide a suitable seal about the stems 31.

The lower ends of the stems 31 are formed with sockets 35 adapted to receive the balls 36 of self-seating members 37 whose opposite seating surfaces are conical and are preferably formed from carbide, or similar abrasive and corrosion resistant materials. The ball and socket association of the seating members 37 with the stems 31 will insure the proper seating of the members 37.

15 by dowel pins 38 and spaced therefrom to provide a chamber 39 between these members. The central threaded bore 24 in the head 15 communicates with the chamber 39, as shown in Figure 1. A plurality of ported seats 40 are removably arranged in the disk 14 and positioned to correspond to the seating members 37 thereabove. The seats 40 are bevelled, as illustrated in Figure 1, and are preferably of a relatively hard material, such as carbide, which has exceptional wear and corrosive resisting qualities. It is also desirable that these members be renewable.

The ports 41, in which the seats 40 are arranged, open through the disk 14 into the compartment 42 defined therebeneath. The ports 41 preferably are of different diameters and flared at the undersurface of the disk 14 to minimize the resistance to the flow of well fluid therethrough. The variations in diameters of the ports 41 afford a more effective means for controlling volume of flow.

A plurality of grooves 43 are formed around the interior of the upper end of the body 10 for packing rings 44 which provide for a seal around the head 15. A similar groove 45 is formed in the inner surface of the head 15 about the disk 14 to receive a packing ring 46 providing a suitable seal around the disk 14. The well fluid enters the chamber 39 through the bore 24 and imposes a constant pressure upon the disk member 14, passing through the ports 41 and the compartment 42 and out through the nipple 12 and the pipe connected thereto to storage.

Obviously, the stems 31 can be selectively threaded downwardly to close the ports 41 by the self-sealing members 37, either completely or only partially, to control the flow of well fluid through the invention. Each of the stems 31 have suitable wrench hold surfaces 47 formed on their upper ends, as shown in Figures 1, 2, 3 and 6.

Manifestly, the structure herein shown and described is capable of certain changes and modifications by persons skilled in the art without departing from the spirit and intent of the invention or the scope of the appended claims.

What is claimed is:

1. In a flow control device for oil wells, in combination with a cylindrical body having a reduced portion on one end for connecting the same into an oil line, a flow passage through said reduced portion, a control unit comprising a

cylindrical head member formed with a peripheral flange adapted to be seated on the rim of said body opposite said reduced portion, the inner portion of said head extending into said body, a disk member connected to said head and spaced therebelow by dowels, a plurality of different size ports in said disk providing communication through said body for well fluid, each having a seat, a closure member for each port having an adjustable stem, and an internally flanged collar for securing said control unit in said body.

2. In a flow control device for oil wells, in combination with a tubular body having a flow passage therethrough and having a threaded reduced portion for coupling the same to an oil line, a valve unit comprising a head having a threaded bore therethrough coaxial with said reduced portion, the said head having a peripheral flange engageable with the rim of said body opposite said reduced portion and adapted to support said head thereon, a disk having a plurality of different size ports therein, each having a seat, connected to and spaced from said head by a plurality of dowels, a closure for each of said ports and an internally threaded flanged collar for securing said head in said body.

3. In a flow control device for oil wells, in combination, a hollow body having a flow passage therethrough and a reduced portion on one end providing a coupling for an oil line, a circular control head formed with a circumferential flange intermediate its ends adapted to engage the rim of said body opposite said reduced portion to support said head therein, a disk secured to and spaced below said head by dowels and having a plurality of ports therein providing communication through said body, a closure member for each of the ports in said disk, each having an adjustable stem, and a flanged collar threaded upon the upper end of said body securing the said head therein.
